UNITED STATES PATENT OFFICE

117,401

DESIGN FOR A HOLDER FOR A SHAVING SET

Edward B. Long, Jr., and Howard Field Carpenter, White Plains, N. Y.

Application March 22, 1939, Serial No. 83,758

Term of patent 7 years

To all whom it may concern:

Be it known that we, Edward B. Long, Jr., and Howard Field Carpenter, respectively, are citizens of the United States of America, respectively residing in White Plains, county of Westchester, State of New York, have invented a new, original, and ornamental Design for a Holder for a Shaving Set, of which the following is a specification, reference being had to the accompanying drawing, forming part thereof.

In the drawing:

Fig. 1 is a side perspective view of the holder for a shaving set showing my new design.

Fig. 2 is a top plan view of the same.

We claim:

The ornamental design for a holder for a shaving set, as shown.

EDWARD B. LONG, JR.
HOWARD FIELD CARPENTER.
